UNITED STATES PATENT OFFICE.

FREDERICK W. HORSTMANN, OF MAPLEWOOD, NEW JERSEY.

DESIGN FOR A FUR.

Application filed November 17, 1925. Serial No. 15,437. Term of patent 14 years.

To all whom it may concern:

Be it known that I, FREDERICK W. HORSTMANN, a citizen of the United States, residing at Maplewood, in the county of Essex and State of New Jersey, have invented a new, original, and ornamental Design for Furs, of which the following is a specification, reference being had to the accompanying drawing, forming part thereof.

Figure 1 of the drawings is a plan view and Figure 2 is a side view of a fur, showing my new design. Figure 3 is a front elevational view of a fur embodying my design.

The design comprises a series of undulations in a fur, said undulations crossing at right angles so as to present a series of rounded tufts of fur which when viewed present a pleasing contrast of lights and shadows.

I claim:

The ornamental design for a fur, as shown and described.

In testimony whereof, I have hereunto subscribed my name this 14 day of November, 1925.

FREDERICK W. HORSTMANN.
